BOAT LIFT

Wilburn H. Swanson, 1325 Maple Ave.,
Wilmette, Ill. 60091

Filed Mar. 15, 1967, Ser. No. 6,234

Term of patent 3½ years

(Cl. D41—1)

FIG. 1 is a top perspective view of a boat lift embodying my new design; and

FIGS. 2, 3 and 4 are, respectively, a side elevational view, a top plan view, and a front elevational view thereof.

I claim:

The ornamental design for a boat lift, substantially as shown.
